United States Patent Office.

JOHN D. LANE, OF NEW YORK, N. Y., ASSIGNOR TO HORACE EVERETT,
OF PHILADELPHIA, PENNSYLVANIA.

Letters Patent No. 76,474, dated April 7, 1868.

IMPROVEMENT IN THE MANUFACTURE OF TIN BOXES.

The Schedule referred to in these Letters Patent and making part of the same.

TO ALL WHOM IT MAY CONCERN:

Be it known that I, JOHN D. LANE, of the city, county, and State of New York, have invented an Improvement in Blacking-Boxes; and I do hereby declare the following to be a full, clear, and exact description of the same, reference being had to the accompanying drawing, and to the letters of reference marked thereon.

My invention consists of the lower portion of a blacking-box, the flange of which is turned up from and forms a part of the bottom, and is rolled and indented, all as described hereafter, so as to form an available flange, by a much more economical operation than that heretofore practised.

In order to enable others skilled in the manufacture of articles of this class to make my invention, I will now proceed to describe the manner of carrying it into effect. On reference to the accompanying drawing, which forms a part of this specification—

Figure 1 is a sectional view of the improved box, with the upper portion or lid applied to the body, and Figure 2 a plan view of the lower portion of the box.

Similar letters refer to similar parts throughout both views.

In the manufacture of blacking-boxes, of tinned plates, it has been usual to make the lids by forcing disks of the plate through dies, so as to turn down the edge and form a flange for overlapping the lower portion of the box, the latter consisting of a disk of tinned plate, the edges of which are secured to a ring, forming a deep flange, to be overlapped by the flange of the lid.

The most expensive item in the manufacture of ordinary blacking-boxes has been the making of the lower portions, the manipulations required in fastening together the ends of the ring which forms the flange, and in securing the latter to the disk which forms the bottom, rendering the manufacture on the old plan a matter of serious expense in establishments where large numbers of these boxes are required. The flange of the lower portion of the box being deeper than that of the lid, and having to sustain the internal pressure of the contents, it has heretofore been deemed necessary to make the said flange of the lower portion in the costly manner described, instead of forming it in one piece with the bottom, as in making the lid. I have, however, found that a substantial and uniform flange may be formed on the lower portion of the box, by making it of the same piece as the bottom.

In the drawing, A represents the lower portion of the box, and B the lid, the latter being made in the usual way, that is, by forcing a disk of tinned plate through dies, and thus forming the shallow flange, which overlaps the flange of the lower portion A of the box, as best observed on reference to fig. 1. In making the lower portion A of the box, I, in the first place, adopt precisely the same plan as in forming the lid, that is, I force a disk of tinned plate through dies, thereby turning up the flange, which is of the same piece as the bottom. The flange, however, as thus far completed, is of such a depth, and so ragged and wrinkled, and wanting in uniformity, that it is not in proper condition to receive the lid; hence another operation becomes necessary. This is the formation of an annular indentation, b, in the inside of the flange, and a corresponding projection on the outside, by subjecting the flange to the action of suitable rollers.

This operation, which is rapidly accomplished, serves the twofold purpose of imparting uniformity to the flange, and of permanently strengthening the same, by forming on it the annular projection described.

I claim as my invention, and desire to secure by Letters Patent—

The lower portion of a blacking-box, having a flange turned up from and forming a part of the bottom, and that flange rolled and indented, all as described for the purpose specified.

JOHN D. LANE.
